CANCER CELL SCREENING SELF
COLLECTION INSTRUMENTJudith L. Ladinsky, 4706 Regent St.,
Madison, Wis. 53705

Filed Oct. 4, 1967, Ser. No. 8,882

Term of patent 7 years

Int. Cl. D24—02

U.S. Cl. D83—12

FIG. 1 is a perspective view of a cancer cell screening self collection instrument, showing my new design;

FIG. 2 is a side elevation of a modified embodiment of the instrument illustrated in FIG. 1; and

FIG. 3 is a top plan view of both embodiments.

I claim:

The ornamental design for cancer cell screening self collection instrument, as shown and described.
